UNITED STATES PATENT OFFICE

JOHN H. PLUNKETT, OF LOS ANGELES, CALIFORNIA

REENFORCING STUCCO AND PLASTER BACKING

Application filed March 9, 1927, Serial No. 173,804. Renewed July 15, 1930.

This invention relates to building materials and more particularly to backing sheets upon which to apply stucco or plaster coatings.

Heretofore it has been the practice when applying stucco and plaster to walls and the like, to provide first a substitute for lath which commonly has consisted of a sheet of fabric such as building paper applied to the studding and a layer of poultry wire or other reticulated material applied over the fabric. But each of these materials has been applied separately and therefore their application has required two periods of time, thus unnecessarily increasing the labor cost of construction.

An important object of this invention is to produce a wall backing construction that will effectually provide for all expansion and contraction of the same after the application of plaster thereto.

Another object of the present invention is to reduce by approximately fifty per cent the time required for applying the backing materials which compose the lath substitute. Another object is to cut down waste of materials at the time of their application. Another object is to provide a backing which may not only be applied in less time than heretofore, but one which also shall have deadening properties and may serve as a deadening felt either under plaster or stucco, or elsewhere in walls or even in floors.

Briefly stated, these objects are attained by means of a multiple-ply structure comprising a base sheet and an outer sheet cemented thereto by means of spaced strips of adhesive material, preferably asphaltic, which extend longitudinally between the sheets and in which is embedded a layer of poultry wire or other meshed or reticulated preferably metallic material which is capable of imparting great strength to the backing unit. The base sheet is of a material capable of being positioned against studding, and the outer sheet is of material well adapted for receiving plaster or stucco and for this purpose preferably is thin enough to yield somewhat and to be pressed about

the wire or other mesh employed between the sheets. The invention resides not only in the features above outlined but also in any other novel features which may be herein disclosed.

In the accompanying drawings wherein certain embodiments of the invention are shown by way of illustration only:

Fig. 1 is a face view of a fragment of the backing material showing a portion of the outer thin sheet removed to disclose the base sheet and the strips of asphaltic material applied thereto as well as the layer of poultry wire embedded in the asphalt.

Fig. 2 is a greatly enlarged sectional detail taken on the line 2—2 of Fig. 1 to show the relation of the superimposed sheets, adhesive strips and wire layer.

Fig. 3 is a similar view showing how the backing is applied to studding and also showing a plaster coat thereupon; and

Fig. 4 is a section indicating the use of the laminated structure when applied between top and sub-flooring for deadening purpose.

This laminated backing comprises a base sheet 10, spaced strips 12 extending longitudinally thereof, an outer or facing sheet 14 applied thereover and cemented to the base sheet by the strips 12, and a reticulated reenforcing layer 15 embedded in the adhesive material and held thereby in position between the sheets 10 and 14. The structure so formed is primarily designed as a backing for plaster and stucco coatings, and when so used may be secured to studding by means of staples —S— or the like as indicated in Figs. 2 and 3, the stucco or plaster coat —P— being then spread thereover in any usual manner as indicated.

Many materials may be used both for the base sheet 10 and the outer or face sheet 14, and include light and heavy fabrics both coated and uncoated, saturated and unsaturated felts, asbestos sheets and the like, while cardboard, chipboard and the like may also be included in the list for the base sheet 10. However, a relatively heavier material is preferably used for said base sheet such as a heavier saturated and fireproofed building

felt or paper, while a relatively yielding thin asbestos paper is preferably or at least conveniently employed for the outer sheet 14. In this manner the materials may be made fire-resisting or in any event fire-retarding. The adhesive, as above indicated, preferably is an asphaltic material which may be applied in thick strips 12 and which will set when cold and serve to receive and hold the mesh layer 15. By spacing said adhesive strips 12 and extending them substantially the length of the backing, a structure is provided which cares for expansion and contraction, the uncoated spaces or strips between said adhesive strips 12 acting as expansion and contraction joints. For the reticulated material many metallic structures may be employed, such as the so-called poultry and rabbit wire or netting, metal lath, expanded metal and the like, that illustrated being the poultry or rabbit wire mesh. The thickness, character and strength of the materials obviously will be varied according to requirements.

25 For applying stucco or plaster, the outer sheet 14 should be thin enough and sufficiently yielding that the application of the coating will press said sheet about the meshes of the metal layer 15, the stucco or plaster in some instances possibly even penetrating the sheet, whereby a firm bond or key is assured. At the same time, the material of the sheet 14 must be of such character that the coating will adhere tenaciously thereto and be retained by such adhesion and by suction.

40 The structure has considerable deadening properties, in addition to its functions as a stucco and plaster backing. For this purpose, it may be used also in other connections in walls, floors and the like. In Fig. 4 such a use is indicated where the said laminated structure is applied between a top floor —F— and a sub-floor —F'— solely for the deadening effects obtained.

45 What I claim is:

1. A building material comprising a pair of sheets, strips of cementing material extending in spaced relation between said sheets, and a reticulated reenforcing layer embedded in said cementing material.

50 2. A building fabric comprising a pair of flexible sheets, spaced strips of cementing material securing said sheets together, and a reticulated reenforcing metal layer lying between said sheets and embedded in said cementing material.

55 3. A building material comprising a pair of sheets, strips of cementing material extending in spaced relation between said sheets, and a reticulated reenforcing layer embedded in said cementing material, one of said sheets being relatively thin and yielding for the application of plaster and stucco.

60 4. A building fabric comprising a pair of

flexible sheets, spaced strips of cementing material securing said sheets together, and a reticulated reenforcing metal layer lying between said sheets and embedded in said cementing material, one of said sheets being relatively thin and particularly adapted for the adherence of plaster and stucco coatings.

In witness that I claim the foregoing I have hereunto subscribed my name this 26th day of February, 1927.

J. H. PLUNKETT.
